(57) **CLAIM**

I claim the ornamental design for a race car cell phone holder, as shown.

DESCRIPTION

FIG. 1 is a front view of a race car cell phone holder showing my new design;

FIG. 2 is a right side view of the holder of FIG. 1, the left side view is identical;

FIG. 3 is a top view of the holder of FIG. 1; and,
FIG. 4 is a bottom view of the holder of FIG. 1.
